UNITED STATES PATENT OFFICE.

WILLIAM S. MITCHELL, OF NEW CUMBERLAND, OHIO.

NUT-LOCK.

SPECIFICATION forming part of Letters Patent No. 227,810, dated May 18, 1880.

Application filed February 17, 1880.

To all whom it may concern:

Be it known that I, WILLIAM S. MITCHELL, of New Cumberland, in the county of Tuscarawas and State of Ohio, have invented a new and Improved Nut-Lock, of which the following is a specification.

Figure 1 is a front elevation of the device applied to a fish-plate. Fig. 2 is a longitudinal sectional plan of the same on line *x x*, to Fig. 1.

Similar letters of reference indicate corresponding parts.

This invention belongs to that class of inventions that have for their object the securing of nuts on railroad-tracks, bridges, and machinery, &c.

The invention consists of hinged lock-plates provided with beveled sockets to fit over the nuts, said lock-plates having their free ends locked together by lock and key.

In the drawings, A represents the fish-plate; B B, the bolts passing through the fish-plates; C C the nuts on said bolts. D D are the hinges, which hinge the lock-plates E E to the fish-plate A, and said lock-plates E E are provided with beveled or conical sockets *a a*, that fit over the nuts C, and thereby prevent their turning.

Fastened upon the face of the fish-plate A

is a thin metallic plate, F, that extends, at right angles to said plate A, outward between the inner ends of the lock-plates E E.

G is a lock operated by the key H, which lock G is fixed in the inner end of one of the lock-plates E, while its bolt may be thrown by the key H through an opening in the plate F and into the socket *f* in the end of the opposite lock-plate, so that the said lock-plates, locking the nuts, can be themselves locked securely in position.

In order to remove or turn the nuts C C at any time the said lock-plates E E can be unlocked from each other and thrown back upon their hinges.

Having thus described my invention, what I claim as new, and desire to secure by Letters Patent, is—

The combination, with the plate F, secured to the fish-plate A, of the lock-plates E E, provided with sockets, as described, hinged to the said plate A, and secured in position by lock and key, substantially as herein shown and described.

WILLIAM SHAKESPERE MITCHELL.
